[57] CLAIM

The ornamental design for an electronic trip relay, as shown and described.

DESCRIPTION

FIG. 1 is a front and upper right perspective view of an electronic trip relay showing our new design;

FIG. 2 is a rear and lower left perspective view thereof;

FIG. 3 is a front elevational view thereof;

FIG. 4 is a top plan view thereof;

FIG. 5 is a bottom plan view thereof;

FIG. 6 is a rear elevational view thereof;

FIG. 7 is a right side elevational view thereof;

FIG. 8 is a left side elevational view thereof; and,

FIG. 9 is a front and upper right perspective view thereof shown with the transparent cover in the open position.

FIG. 1

FIG. 2

FIG. 3

FIG. 4

FIG. 5

FIG. 6

FIG. 9
